GAME AND PRACTICE APPARATUS

John F. Vaughan, Belmont, Mass.

Application January 9, 1930, Serial No. 419,564

61 Claims. (Cl. 273—32)

The present invention relates to game and practice apparatus and to methods of operating the same.

The objects of the present invention are to provide a game and practice apparatus which shall be of simple and inexpensive construction, which will provide entertainment for and hold the interest of the participants, which will not only require the exercise of the skill and strength of the players but will develop and improve the same, which will simulate well established games and sports to such an extent as to become an adjunct for the practice of the same or a substitute therefor, which by reason of the limited amount of space required is adapted for home use, both indoors and outdoors, and which on account of its ability to record accurately the results of the player's efforts is particularly adapted for instruction and demonstration uses.

20 With these objects in view the present invention consists in the devices and combinations of devices, and the mode of operation hereinafter described and more particularly defined in the claims.

25 All outdoor games and sports, as a rule, require grounds or fields of considerable area. This is particularly true of those games or sports in which a ball or other article is driven or thrown. The game of golf, for example, is now 30 commonly played over a territory seldom less than fifty acres in extent for small courses and one hundred and fifty acres or more for the larger courses. The average player frequently makes shots of two hundred yards in length, and the 35 more skilful often reach three hundred yards and over. Obviously the playing or even practicing of such a sport in the average player's home grounds or within doors is impossible, and although many previous attempts have been 40 made to provide apparatus which may be used within the confines of private grounds or indoors, either for the purpose of recreation, or exercise, or practice, none of these has thus far achieved any substantial commercial success on account of 45 the inability of the player to determine or measure with reasonable accuracy the results accomplished in terms of his skill and ability.

One form of golf practice apparatus comprises 50 an enclosure usually in the form of top and side nets with a back wall of netting or canvas, the player standing at the open end and driving the ball against the back wall. Such an enclosure or "cage" as it is called is usually installed indoors 55 and is necessarily limited in size, often permitting

the flight of the ball of only fifteen or twenty feet.

No satisfactory method or apparatus has as yet been devised whereby the player may determine the distance his ball would have traveled had he been in the open, this being left entirely to his own judgment and estimate which necessarily is most inexact. The attempt to simulate or imitate a game of golf, or even the play of a single hole, with such an apparatus is hopeless 10 since it necessarily lacks all the features which make the game of golf interesting and fascinating, such as the determination of the length of the tee shot, the carrying of traps and bunkers at definite distances, and the accurate gaging 15 of the shots to the green which vary in distance from the short chip of a few yards to the full shot of two hundred yards or more.

The present invention, on the other hand, provides not only for the determination of the normal distance the ball would have traveled in the open, but may record such distance in a manner which by reason of its analogy or resemblance to the determination of such distance on the actual playing field, adds realism and interest to the 20 use of the apparatus.

Furthermore, the present invention contemplates the determination of direction of flight and also records this, in connection with the distance, in a realistic and highly interesting manner. 30

Still further refinements of the present invention are the providing for the effect of the wind, of varying direction and velocity, so that conditions still further approximate those of actual 35 play and the player is compelled to adapt his shots to such conditions or suffer the consequences in the same manner as upon the golf course itself.

All of these features are combined in a simple, 40 inexpensive apparatus requiring no more space than can ordinarily be found on the player's own ground, or in an attic or cellar, or in a club house, and thus not only will enable one to play a game in many features corresponding exactly to the 45 actual game, but will also permit him to secure practice and instruction at times and under conditions which would itself render play upon the course or practice out of doors impossible.

In the accompanying drawings is shown a form 50 of the present invention as adapted for a golf game and practice apparatus. This comprises, briefly, a netting enclosure or cage, having a back curtain of canvas or other suitable material against which the ball is driven by the player 55

from the open end of the cage. By means of a timing device controlled first by the ball's leaving the tee, and second, by its striking the curtain, the duration of time of flight is actually determined or measured, and from such determination or measurement, the distance the ball would have traveled normally in the open is determined. The normal travel of the ball in distance and direction is visually indicated by means of a spotlight projected upon a plan or representation of the fairway being played, the spotlight being caused to travel by automatic mechanism from the tee or lie on the fairway and toward the hole a distance corresponding to that indicated by the timing mechanism.

The curtain is divided laterally into a number of narrow zones, and by means of suitable mechanism any deviation from the desired direction of the ball so that the latter strikes one or another of these zones causes a corresponding deviation of the spotlight from the straight and correct direction intended.

Mechanism has also been provided which produces on the length and direction of flight or movement of the phantom ball or spotlight an effect simulating that ordinarily carried by the wind on the ball played in the open.

Fig. 1 of the drawings shows in isometric projection the timing and projecting apparatus together with the mechanism for indicating lateral deflection or mis-direction due to failure of the player to drive his ball in the true or desired course, many details being omitted for the sake of clearness; Figs. 2 and 3 are side elevations 90° apart of the actuating spring and dashpot mechanism for the timing and projecting mechanism; Figs. 4 and 5 are isometric views of the wind deflection mechanism, and Fig. 6 is a vertical sectional view of the dashpot for use in connection with the same; Fig. 7 is a side view, largely in vertical section, showing the pedestal for supporting the timing and projecting mechanism and the connections for the wind deflection devices; Figs. 8 and 9 are details on an enlarged scale of the slotted guides and cross-head for actuating the projector from the timing mechanism; Fig. 10 is a fragmentary detail of the timing quadrant showing the stop shoulder and inclined face adjacent thereto; Fig. 11 is a detail on an enlarged scale, largely in vertical section, of the adjustable connections for the wind deflection device, and Fig. 12 is a top plan view of a portion of the same with the top clamping nut removed; Fig. 13 is a vertical longitudinal section on an enlarged scale of the clutch mechanism for rendering the projector actuating devices operative; Fig. 14 is a side elevation of the tee switch which is controlled by the ball at the tee; Fig. 15 is a top plan and Fig. 16 an axial elevation of a modified form of mechanism for indicating a varying extent of deflection of the ball from the true course; Fig. 17 is a side elevation of the same; Fig. 18 is a fragmentary detail of the mechanism shown in Fig. 16; Fig. 19 is a vertical section on line 19-19 of Fig. 16 on an enlarged scale; Fig. 20 is a top plan of the cage and other apparatus; Fig. 21 is a side view of the same on line 21-21 of Fig. 20; Fig. 22 is an end view of the cage as seen by the player; Fig. 23 is an enlarged side elevation showing the arrangement of the back curtain, the supplementary curtain, and one of the curtain switches; Figs. 24 and 25 are a top plan and a vertical section respectively on enlarged scale of the closed curtain switch used behind the screen and opposite the middle there-

of, while Figs. 26 and 27 are corresponding views of the open curtain switches employed at each side of the middle; Fig. 28 is a diagrammatic view of the electric wiring for the apparatus, and Fig. 29 is an enlarged view of the back screen showing at one side thereof the representation or plan of the fairway or hole being played.

The apparatus illustrated in the drawings comprises four major parts, the timer for measuring or determining the distance the ball would have traveled normally in the open, the projector for indicating visually the distance and direction of flight of the ball, the director for determining and through the projector indicating the direction of the ball whether straight or to one side or the other of the true or desired course, and the wind deflection device for imparting and indicating through the projector the effect of the predetermined direction and velocity of the wind.

The control devices for the timer, projector, director, and wind deflection device are all electrically operated. The requisite power for actuating the timer, projector, and wind deflection device is supplied from springs. The power for the director is electric.

In Fig. 1 is shown in perspective a tilting and swiveling, flat base 31 upon which are mounted the timing, projecting and directing mechanisms. This base is supported on the vertical spindle 32, see Figs. 4 and 7, mounted in the pedestal 33.

The timer comprises a quadrant 34 mounted to rotate in an anti-clockwise manner, as viewed in Fig. 1, under the influence of the coiled spring 35, the rate or speed of movement being controlled by the dashpot 36. This dashpot, see Figs. 2 and 3, is of the hydraulic type containing oil or other suitable liquid, and comprises a piston 37 fixed to the end of piston rod 38 and having a plurality of holes or apertures 39. An imperforate disk 41 fitting loosely on the piston rod 40 normally rests upon the top of the piston 37 and closes apertures 39. When the piston is descending, however, the disk 41 lags behind, thereby uncovering the openings 39 and facilitating the downward movement of the piston and rod.

The piston rod projects through the closed top of the dashpot and is connected at 42 to a strap or other flexible connection 43, the opposite end of which is secured at 44 to the drum 45 fixed upon one end of the shaft 47 which carries at its opposite end the quadrant 34. The inner end of the spiral spring 35 is secured to the shaft while the outer end is held in fixed position by the pin 48 mounted in the arm 49 on the cylindrical sleeve or bearing 51 at the upper end of the support 52 mounted upon the base 31.

Provision is made in the dashpot for the flow of liquid from a point above to a point below the piston during the operating or upward stroke of the latter, and this is accomplished by means of a by-pass or pipe 54, the lower end of which enters the bottom of the dashpot below the piston, while the upper end enters the side of the dashpot above the piston. The rate of flow through this by-pass or pipe is regulated to control the rate of movement of the piston within the dashpot by means of the valve 55 adjustably mounted in the lower end of the lever 56 pivoted within the dashpot at 57. The valve 55 by means of its threaded shank and knurled head may be adjusted to give the desired opening and rate of flow.

The purpose of the lever upon which the valve is mounted is to provide for the bodily movement of the valve during the upward movement of the

piston so that a faster movement of the dashpot can be secured during the earlier or timing portion of its stroke, and a slower movement during the latter portion, for a purpose shortly to be explained. It is the movement of the quadrant under the influence of the coiled spring, and controlled by the dashpot, which is utilized to measure or determine, and through the action of the projector, to indicate the potential distance of travel of the ball. This is accomplished as follows.

Fixed in the quadrant is the crank pin 61 for actuating the cross-head 62 upon the end of the rod 63. The opposite end of this rod slides or telescopes within the hollow end of shaft 64 fitting loosely therein. The rod and shaft may, however, be locked or clamped together by means of clutch devices. As shown in Fig. 13, these comprise the locking washer or disk 65 having a central opening slightly larger than the rod 63 upon which it is mounted and with squared inner edges or corners so that while the rod may slide freely through the disk when the latter is held at right angles to the rod, a tipping or tilting of the disk will cause it to bite and grip the rod securely. The disk is held at its upper edge by the shoulder 66 on the shaft 64 and is tilted by coiled compression spring 67 mounted in the counter-bore in the end of the shaft 64. The clutch disk 65 is held in inoperative position by means of the collar 68 loosely mounted on rod 63 and provided with beveled faces. Collar 68 is controlled by bell-crank lever 69 pivoted on pin 71 mounted in a fixed support which for clearness of illustration is omitted from the drawing. When the lever 69 is moved in a clockwise direction, the beveled end of its short horizontal arm engages the collar 68 and forces it to the left in Fig. 13, compressing spring 67 and releasing rod 63 from the clutch disk 65 and permitting sliding movement of rod 63 within shaft 64.

On movement of lever 69 in the opposite direction, coiled spring 67 causes clutch disk to tilt and lock rod 63 and shaft 64 rigidly together. In operation lever 69 will be actuated to free the rod 63 during the earlier or timing portion of the stroke of the dashpot and quadrant, and to lock or clamp the rod 63 to shaft 64 during the latter or projecting portion of the stroke of dashpot and quadrant.

The determination or measurement of the potential flight of the ball is based upon the time interval which elapses between the ball's leaving the tee and striking the back curtain. Since the higher the velocity of the ball the shorter is the time interval and the longer is the flight of the ball. Accordingly it was necessary to devise some means whereby the shorter intervals would indicate longer flights. This I have done by taking a uniform or constant throw or movement of the dashpot and quadrant and making the first portion of such stroke, which corresponds in duration to the time interval of the ball's flight from the tee to the curtain, whatever that may be, an idle or waste movement or stroke. The remainder of the full stroke is then used to measure and to indicate the length of flight of the ball. Obviously, the harder the ball is struck and the swifter its flight from the tee to the curtain, the shorter will be the time interval and the corresponding idle and waste portion of the stroke of the dashpot, and the longer will be the measuring and indicating portions of such stroke. An easily struck ball, on the other hand, with slower flight will consume correspondingly greater time

in traveling from the tee to the curtain, and a similarly increased idle or waste portion of the dashpot stroke will occur with a corresponding reduction in the length of the measuring and indicating portion of such stroke.

It is the pivoted lever 69 and the clutch disk 65 for clamping the rod 63 to shaft 64 which control the measuring and indicating action of the apparatus. When the ball is struck the rod 63 is unclamped and slides freely within the shaft 64 as the cross-head 62 begins its initial movement under the action of spring 35 controlled by the dashpot 36. During this portion of the stroke the shaft 64 remains stationary, but the instant the ball strikes the back curtain lever 69 is actuated to release spring 67 which promptly causes disk 65 to grip or clamp the rod 63, thereby locking the rod and shaft together so that the continued movement of the cross-head under the action of the quadrant imparts a longer or shorter axial movement to the shaft 64 in extent corresponding to the speed of the ball, and therefore adapted to indicate the distance or length of normal flight.

In the apparatus illustrated in the accompanying drawings, no provision has been made to indicate directly in yards the distance of travel, but instead a spotlight or phantom ball has been provided which, for each shot or stroke, will move over a plan or map or other representation of the fairway or hole being played from the point on the map corresponding to the position where the shot is played, whether at the tee or along the fairway, stopping at the point or position corresponding to the place where the ball would have come to rest in the open, the player estimating the length of his drive or other shot just as in the actual game by reference to landmarks or definitely positioned markers.

The projector mechanism for this spotlight or phantom ball comprises the projector or cylinder 75 mounted upon trunnions or horizontal pivots 76 in the yoke 77 at the top of hollow stem 78 free to turn upon the spindle 79 fixed in the base or slide 80. The cylinder 75 thus has provision for universal movement. Within the cylinder at its right hand end as viewed in Fig. 1 is mounted a small incandescent lamp bulb 81, supplied in any suitable manner with electric current, while at the opposite end is the lens 82 for projecting the spot of light from the bulb upon the representation or plan of a fairway or hole as indicated by the supplementary screen or curtain 83 covering a portion of the main screen 84, as shown in Fig. 29.

The mechanism for actuating the projector to cause the spotlight or phantom ball to travel along the picture or plan of the fairway, comprises the yoke 85 secured to the end of the shaft 64 and having the angularly disposed guides 86 forming the slots 87. Rigidly secured to the right hand end of the projector cylinder is the hollow stem 88 within which is slidably mounted the tail rod 89 carrying at its end the stud 90, and check-nut 91. Pivoted upon the stud and free to turn is the block or cross-head 92 fitting between the guides 86 with a sliding fit, and carrying upon the opposite sides the pins 93 which enter and are guided by the slots 87 in the yoke 85.

The above described construction is such that when the shaft 64 and yoke 85 are moved axially, the pins 93 through engagement with the slots 87 produce a tipping movement of the projector to cause the spotlight or phantom ball to travel over the screen. Since the extent of movement

of the shaft 64 varies with the velocity or speed with which the ball travels the distance from the tee to the screen, it follows that the extent of movement of the phantom ball on the screen affords an accurate basis for comparison of the different strokes and by a proper positioning and adjustment of the apparatus parts, the extent of movement of the phantom ball may be made to indicate accurately the actual distance in yards 10 the ball would have traveled normally in the open.

Furthermore, since the latter portion of the movement of the pin 61 on the quadrant 34 is utilized to cause this tipping of the projector, as this pin approaches the limit of its rotational movement, which limit is on center, the rectilinear movement of the yoke 85 will be at a progressively diminishing rate, until the parts come to a gradual and easy stop. This motion transmitted through the inclined guides 86 on the yoke 85 20 will result in a similar slowing down and gradual stopping of the tipping movement of the projector, producing a most realistic effect on the screen of the slowing down and final stopping of the ball at the end of its flight and run.

25 In order to provide for variations in the distance or travel of the ball in accordance with the "loft" of the club which is used, the base 80 upon which the projector is supported is made adjustable, being movable in a guideway 94 on the base 30 31, a locking screw 95 securing the base in the desired adjustment. The telescoping connection between the stem 88 and the tail rod 89 is for the purpose of allowing such longitudinal adjustment of the projector.

35 It is obvious that as the base and projector are moved toward the left, as viewed in Fig. 1, the amount or extent of its angular tipping, due to the increase in the distance from the trunnion 76 to pins 93, will be diminished and the same extent or range of longitudinal movement of the shaft 64 and yoke 85 will now produce a shorter flight or travel of the phantom ball on the screen. Conversely, adjustment of the projector to the right will result in greater distance indicated by 45 the phantom ball.

Accordingly, when tee shots are made with the driver or other wooden club, the projector will be positioned at the limit of its movement to the right so that the maximum distance will be rendered. For the various iron clubs, such as the mid-iron, jigger and mashie, the projector will be adjusted more and more to the left to diminish the indicated travel of the ball in accordance with the conditions and results in actual play.

55 A scale, as shown at 96, may be provided so that the projector may be set accurately and invariably at the proper distance for the club then being used.

The control of the timing and projecting mechanisms through electrical devices is effected as follows: Pivoted upon the stud 97 carried by a supporting bracket (not shown) at the right hand end of base 31 as viewed in Fig. 1, is the latch lever 98 provided at its upper end with a catch 99 60 adapted to engage a shoulder 100 on the periphery of quadrant 34, when the latter is rotated in a clockwise direction by the setting handle 101 against the tension of coiled spring 35.

70 Mounted upon the base 31 is the timing solenoid 104 within which is mounted the movable core 105 on the rod 106 the end of which is connected with the lower end of the latch lever 98, being adjustable with relation thereto by means of the knurled nuts 107. Near the solenoid the rod 106 75 is connected to the lower end of the vertical arm

of bell-crank lever 69 which controls the clutch between the rod 63 and shaft 64, the abutment nuts 108 being adjustable to permit the proper timing of the clutch. A coiled tension spring 109, one end of which is connected to a fixed pin 5 111 and the other to the lever 69, tends to hold the solenoid rod 106 in such position that lever 69 will render the clutch operative and the rod 63 and shaft 64 will be connected and also so that the latch lever 98 will be in locking position with 10 the catch and shoulder 100 in engagement and the quadrant held from movement.

When the ball is struck from the tee an electric current is caused to flow through the timing solenoid 104 causing movement of the core 105 15 to the left and through the solenoid rod 106 actuating the latch lever 98 to release the quadrant, and at the same time actuating lever 69 to throw the clutch out of operation. During the flight of the ball from the tee to the screen the 20 current continues to flow through the timing solenoid and since the rod 63 remains disconnected from the shaft 64, no movement of the projector takes place. The instant the ball strikes the screen, however, the circuit through 25 the solenoid is broken and the spring 109 moves the core and rod in the opposite direction to throw the clutch into operation, whereupon the rod 63 and shaft 64 are immediately connected and the continued movement of the quadrant 30 sets the projector in motion and reproduces upon the screen the flight or travel of the ball.

The quadrant is provided with a second shoulder 306 which will be engaged by the catch 99 on the lever 98, the latter having been thrown 35 into operative position by the spring 109 when the timing solenoid circuit was broken, and acting to stop movement of the quadrant and connecting mechanism, including the projector.

The timing solenoid 104 also controls the by- 40 pass valve 55 in dashpot 36 so that the valve will be opened when the solenoid is energized, that is, during the flight of the ball from the tee to the curtain, and will be closed, partially or wholly, when the solenoid is de-energized, that is when 45 the ball strikes the back curtain. This timing results, on the one hand, in a faster action of the dashpot during the timing portion of the stroke or movement of the quadrant, thereby securing greater accuracy in timing, and, on the other 50 hand, in a slower action of the dashpot during the projecting portion of the stroke of the quadrant, thus accurately reproducing, so far as time duration is concerned, the flight or travel of the ball in actual play and thereby adding to the 55 realistic effects secured.

The actuating mechanism for the by-pass valve comprises the vertical lever 112 pivoted on the fixed pin 113 mounted in a bracket (not shown) on the machine. The upper end of this lever 60 is connected by means of the link 114 and abutment nuts 115 with the upper end of the valve lever 56. The lower end of the lever 112 is connected by the arm 116 and abutment nuts 117 with solenoid rod 106. The adjustment of these 65 parts is such that when the timing solenoid 104 is energized, the movement of the solenoid rod opens the by-pass valve 55 and holds it open until the ball strikes the curtain, whereupon the timing solenoid is de-energized and the valve rod 70 under the action of the spring 109 causes the valve 55 to close.

The electrical connections which control the flow of current to the timing solenoid 104 (indicated diagrammatically in Fig. 28) comprise the 75

tee switch shown in Fig. 14, and the curtain switch or switches, shown in Figs. 24 to 27. These switches are actuated by the ball itself, the tee switch by the ball's leaving the tee, and the curtain switch by the ball's striking the curtain. The tee switch is provided with the solenoid 118 which is in circuit with the timing solenoid 104. The switch is so constructed that it is held open while the ball is resting upon the tee, but the instant the ball is struck and leaves the tee the switch will be closed and held closed by the tee switch solenoid 118 until the circuit is broken at some other point. The curtain switches are also in circuit with the solenoid and tee switch. In the simplest form of apparatus, where lateral deflection from a straight course is not to be indicated, the curtain switch or switches, if more than one is employed, will be of the closed type, that is, will remain normally closed but will be opened by the impact of the ball on the curtain, thereby breaking the circuit through the timing solenoid 104 and starting the projector in operation.

The tee switch, as shown in Fig. 14, comprises a solenoid 118 having a movable core 119 and rod 121, to the end of which is connected the spiral spring 122 and flexible cord or string 123 carrying the light pad or disk 124. This pad will be placed upon the tee 125 and the ball 126 positioned upon the pad the proper distance from the tee switch to put tension on the spring 122 for a purpose shortly to be explained.

Mounted at 127 on the frame 128 of the switch but insulated therefrom is the spring contact member 129 to which one end of the solenoid winding is connected. The solenoid rod 121 extends rearwardly through the solenoid and through the upper end of the contact member 129, two stop members 131 and 132 being mounted on the rod. A contact screw 133 is mounted in the frame and adapted to be engaged by the end of the contact member 129. A second screw 134 is also mounted in the frame but insulated therefrom, and is also adapted to be engaged by the spring member 129 and to act as an adjustable stop. The position of the parts when the ball is teed up and preparatory to being struck is indicated in Fig. 14, in which the spring member 129 is held by the tension of the spring 122 to the left of the position it would normally tend to take, and out of engagement with both contact screw 133 and stop screw 134. When the ball leaves the tee the light pad or disk 124 is released, the tension of the spring 122 is removed, and the contact member 129 springs to the right a sufficient distance to contact with both screws 133 and 134. Instantly the circuit is closed and the current flowing through the wires 135 energizes the solenoid which tends to draw the core still further to the right and to hold the spring member firmly in engagement with the contact screw 133, this condition continuing while the ball is in flight from the tee to the screen.

The closing of the circuit through the tee switch completes the circuit through the timing solenoid 104, releasing the quadrant and setting the timer mechanism in operation and during the time interval of the flight of the ball from the tee to the screen this timing solenoid remains energized, holding the rod 63 and shaft 64 disconnected so that the movement of the quadrant is without effect upon the projector mechanism.

The breaking of the circuit when the ball strikes the back curtain to de-energize the timer

solenoid 104 and connect the rod 63 and shaft 64 to set the projector in motion is accomplished through the following mechanism.

Suspended behind the curtain and in close proximity thereto are a number of flexible cords, the middle cord indicated at 138 and the cords on each side at 139 (see Figs. 22 and 23). These cords are fastened at their top to some fixed support and carry suspended at their bottom the curtain switches. The middle cord 138 carries the normally closed switch shown in Figs. 24 and 25, while the side cords 139 carry the normally open switches shown in Figs. 26 and 27.

The closed curtain switch indicated generally at 141 comprises a rectangular block or weighted member 142 of wood or other suitable material. Fastened to the top of the block is the metal plate 143 to which one of the leads 144 is connected. The block is provided with a central bore within which is mounted the insulated bushing 145. An insulated plate 146 is secured to the bottom of the block. Loosely fitting within the bushing is the screw 147 to which is connected the other lead 148 by means of the clamping nuts 149. A leaf spring 151 is mounted under the head of the screw 147 and bears at its ends upon the bottom of the block, acting normally to hold the lower clamping nut 149 in contact with the plate 143 and the circuit through the leads 144 and 148 closed.

The cord 138 is connected to the upper end of the screw 147 by means of the link 152, the switch structure hanging suspended on the lower end of the cord and maintaining the latter straight and tight in close proximity to the back of the curtain. The tension on the leaf spring 151 is adjusted by means of the clamping nuts 149 so that when the switch is so suspended the circuit will still be closed, and when a ball strikes the screen near the cord, the bulging of the screen will cause a corresponding deflection of the cord and the inertia of the switch, due to its weight, will result in the momentary separation of the contacts on the switch and the opening of the circuit.

Since the curtain switch 141 on the middle cord 138 is in the circuit with the tee switch, the instant the circuit is opened by the ball striking the curtain, the tee solenoid 118 is de-energized and the spring member 129 leaves the contact screw 133, permanently opening the circuit. When the curtain switch 141 again closes, as it quickly will when the curtain and cord straighten or flatten out, the circuit will still remain broken because the normal position of the contact member 129 of the tee switch is out of contact with the contact screw 133, as shown in Fig. 14.

This breaking of the circuit when the ball strikes the back curtain de-energizes the timer solenoid 104, permitting the clutching together of the rod 63 and shaft 64, so that continued movement of the quadrant operates the projector to indicate the potential flight of the ball.

Thus, the action of the ball in leaving the tee sets the timer mechanism in operation, and the striking of the ball against the back curtain sets the projector mechanism in operation. The movement or stroke of the quadrant is constant and continuous and comprises two portions, the former or timing portion and the latter or projecting portion, the point of division being fixed by the ball's striking the back curtain. Obviously the harder the ball is hit and the swifter its flight from the tee to the curtain, the shorter

will be the timing interval and the longer will be the projecting interval, with the resulting indication of a correspondingly longer flight or distance of the shot.

5 If it is desired to indicate only the distance of each shot without regard to the direction, the mechanism thus far described is all that is required, and comprises the timer, the projector, the tee switch, and the closed curtain switch.

10 Preferably, however, the direction of flight of the ball will also be indicated so that the player will know whether he is driving the ball straight and true or more or less to one side or the other. The mechanism for indicating such deflection

15 comprises, briefly, the side curtain switches, which control means for imparting a slight rotational movement in one direction or the other to the shaft 64 and its yoke and inclined guides, so that movement of these parts will impart a 20 slightly oblique tip to the projector mechanism causing the spotlight or phantom ball to be deflected slightly from the intended straight and true path.

These side switches, shown generally at 153, 25 are normally open and are very similar to the normally closed middle switch 141, comprising the same block 142' with central opening, and insulated bushing 145', screw 147' loosely mounted therein carrying the leaf spring 151' at its 30 bottom, and connected by the link 152' at its top to the cord 139. The lead 148' is similarly connected to the screw by means of the clamping nuts 149'. Instead, however, of the metal plate on the top of the block these side switches 35 are provided with an insulating top 154 and bridge contact 154' to which is secured the lead 144'.

In Fig. 1 this direction mechanism is shown with parts omitted for the sake of clearness. In 40 Figs. 15 to 19 a modification is illustrated.

Referring to Fig. 1, a ratchet wheel or disk 155 having the hub 156 is mounted upon the shaft 64, the hub being grooved to receive the key or feather 157, so that rotation of the disk will cause 45 rotation of the shaft 64, yet the shaft is free to move through the disk. Pivoted upon the hub 156 is the pawl carrying lever 158 having at its lower end the pivoted double pawl 159 controlled by the springs 161. The forked extension 50 162 on the pawl is adapted to be engaged by one or the other of the collars 163 on the rod 164 of the deflector solenoids 165 and 166. When the solenoid 165 is actuated, double pawl 159 will first be turned on its pivotal support on lever 158 55 until the nearer pawl, as viewed in Fig. 1, engages the toothed periphery of ratchet disk 155, whereupon continued movement of the solenoid rod will move said pawl bodily, swinging pawl lever 158 at the same time and imparting a rotational movement to the shaft 64 and its yoke and guides. If the solenoid 166 be actuated, the disk and shaft with its attached parts will be rotated in the opposite direction.

The solenoids 165 and 166 will be each in circuit 60 with its appropriate curtain switch, one on one side of the curtain and one on the other, so that if the ball is driven off direction and strikes to either side of the middle of the curtain, the projector actuating mechanism will be automatically 65 adjusted to indicate deflection in the proper direction.

Preferably this deflection indicating mechanism will be constructed to indicate varying extents or amounts in deflection, and in Figs. 15 to 75 19 is shown a modification designed to indicate

three different degrees of deflection on each side of the middle. With this construction the curtain is divided laterally into a series of zones, each zone having its own drop cord, curtain switch, and solenoid for indicating the direction 5 and extent of deflection corresponding to the position of the zone struck by the ball.

In this construction in place of the two solenoids 165 and 166 for imparting angular movement through the toothed disk to the shaft, two 10 tension springs are used, the extent of movement being controlled by means of the six solenoids, three for one side of the curtain and three for the other.

In Fig. 15 is shown the deflection indicating 15 mechanism in top view; the same parts viewed in end elevation from the projector end are shown in Fig. 16, and a side elevation in Fig. 17. The main parts of this mechanism comprise the disk 171 for rotating the shaft, the actuating lever 20 172 for the same, and the friction bar 173 and connections for frictionally connecting the actuating lever 172 and disk 171.

The disk and levers are mounted as follows: Splined upon the shaft 64 is the flanged sleeve 25 174, and the disk 171 is screwed upon the threaded end of this sleeve into engagement with a shoulder, and is locked from rotational movement on the sleeve by means of the nut 175. Pivoted midway its ends upon the sleeve 174 is the horizontal actuating lever 172 provided with a vertical handle 176. A washer 177 spaces this lever from the disk 171. The sleeve is itself pivotally mounted in a bearing indicated at 178.

The lever 172 is actuated or tilted by means of 35 tension springs 179 and 180 secured at their lower ends to the adjustable collar 181, screwed upon the threaded lower portion 182 of the rod 183. The upper end of the spring is secured to the flanged sleeve 184, fitting loosely on the upper 40 portion of the rod 183, and connected at its upper end to the actuating lever 172 near its end. A vertical latch lever 186 pivotally mounted at its lower end is provided with a catch or shoulder 187 at its upper end, adapted to engage beneath 45 the flange 188 of the sleeve 184 to hold said sleeve against the downward pull of the spring 179. The latch lever is actuated by means of the link 189 connected at one end to the latch lever 186 and at its opposite end to the U-shaped lever 191 50 pivoted on the base of the machine and having its ends connected with the flat horizontal solenoid bar 192. This bar 192 rests upon the rods 194 extending from the cores 195 of the solenoids 196, the ends of the rods being threaded to receive the adjustable abutment nuts 197 which engage the edge of the solenoid bar 192.

The above described construction is such that if either one of the three solenoids 196 be actuated, the solenoid bar 192 will in turn be actuated 60 and through the lever and link connection trip the latch to release the flanged sleeve 184.

A similar and corresponding construction is provided for the other end of the actuating lever, whereby when any of the solenoids 198 are actuated the flanged sleeve 190 for spring 180 will be unlatched.

An arm or lever 199 fixed upon the horizontal portion of the U-shaped levers 191 and carrying at its free end the adjustable abutment screw 70 199' controls switch 200, holding the switch closed against the opening action of its spring arms when the parts are set ready for operation as shown in Fig. 17, all for a purpose hereinafter to be described.

When the apparatus is set ready for use, both latches will be in action, anchoring both flanged sleeves against the downward pull of their respective springs. The upward pull of each spring 5 exerted through collars 181 and rods 183 then balance and the lever is held in neutral horizontal position. When the ball strikes the rear curtain to one side of the middle, one of the solenoids 196 or 198 will be energized, thereby tripping one of the latches and releasing its flanged sleeve which is instantly drawn downwardly by 10 its spring. The other spring, now being relieved of the balancing pull of the first spring, immediately becomes operative and contracts. Since its 15 upper end is anchored to the flanged sleeve which is held by its latch, the contracting of the spring pulls collar 181 upwardly, lifting the rod 183 and tilting lever 172.

The devices for transmitting the tilting or 20 angular movement of the actuating lever 172 to disk 171 to cause the desired angular movement of shaft 64 include a friction bar or member 173 connected to the actuating lever and provided with frictional surfaces which engage the face 25 of the disk. This bar extends across the face of the disk on the projector side but out of contact, and is connected at each extremity with the actuating lever which is on the opposite side of the disk by means of pins 201 on the actuating 30 lever adjacent each end and passing through the ends of the friction bar. Clamp screws 202 on the threaded ends of these pins are adjustable to draw the friction bar towards the actuating lever with greater or less pressure. Fixed upon the 35 disk side of the bar 173 are friction pads 293 adapted to engage the face of the disk near its periphery with sufficient friction so that when the actuating lever is tilted by the springs 179 or 180, the disk will also be tilted, yet providing a yielding 40 connection between these parts to permit their relative adjustment in setting the apparatus.

The mechanism for controlling the extent of tilt of the actuating lever and disk to produce 45 deflection of the phantom ball corresponding in extent to the deflection of the real ball, comprises two sets of solenoids of three each, indicated in Fig. 15 at 196 and 198, solenoids 196 indicating deflections to the right while solenoids 198 indicate deflections to the left. The cores of each of these solenoids carries at its 50 end towards the disk a stem or pin 205 having at its extremity a bevelled head or small disk 206. These heads normally stand, as shown in Fig. 15, 55 out of the plane of movement of the actuating lever 172, but when one of the solenoids is energized as a result of the ball striking the back curtain, the head 206 will be moved through such plane to bring the stem 205 into the path of movement of the actuating lever so when the latter is tilted by the action of one or the other of the springs 179 or 180, the stem will serve as an abutment or stop to limit the extent of tilting movement of the lever and disk 171.

60 The three solenoids on each side of the shaft are so arranged and located that different degrees of tilting will be permitted by the different solenoids, as illustrated in Fig. 18, which shows the middle solenoid as energized and the stem 65 of its core in position to be engaged by the arm of the actuating lever to stop the lever in the position indicated in dot and dash line. It is obvious that if the outside solenoid has been energized a less tilting of the actuating lever would 70 have been permitted, while if the inner solenoid 75

had been energized a greater tilting would have resulted. By connecting the inner solenoid to the curtain switch controlling the extreme outside zone, the middle solenoid to the switch for the middle zone, and the outside solenoid to the 5 switch of the inner zone, all on one side of the middle of the curtain, different degrees of tilting of the actuating lever and disk will be produced in accordance with different degrees of actual deflection of the ball from the middle zone, 10 and corresponding degrees of deflection will be indicated by the phantom ball through the rotation or tipping of the shaft 64 and the inclined guides for the projector.

A similar set of three solenoids is positioned 15 on the other side of the shaft and similarly connected up with their corresponding curtain switches to indicate deflections of varying degrees, but in the other direction.

While in the illustrated embodiment six of 20 these deflection solenoids are employed, whereby three different degrees or extents of deflection to one side or to the other may be indicated, a greater or less number may be employed if desired, giving correspondingly finer or coarser 25 gradations in deflections indicated by the phantom ball.

It will be observed that a single solenoid controls not only the extent of tilting of the actuating lever, but also its release. While the time 30 interval between the actuation of the solenoid and the spring's coming into action to tilt the actuating lever is almost infinitesimal, nevertheless it is sufficient to insure the stem 205 on the solenoid core being in position to be engaged 35 by the tilting lever when the latter is actuated by the spring.

The deflection mechanism is "set" for operation by means of the handle 176 which is swung first to one side and then to the other. The lifting movement of the end of the actuating lever raises the actuating rod 183 until the intermediate collar 209 engages the flanged sleeve 184, whereupon continued upward movement will lift the sleeve and carry its flange above the latch so 45 that when the actuating lever is returned to normal horizontal position the spring will be held under tension. First one spring and then the other will be tensioned in this manner, the movement of the actuating lever at this time being unimpeded by the stems on the cores of the deflection solenoids because these stems all stand retracted, as shown in Fig. 15, under the action of the tension springs 210.

The purpose of heads 206 on the stem 205 is to 50 prevent withdrawal from the stem from beneath the actuating lever 172 when the solenoid is de-energized, which occurs almost instantly after energization. If such withdrawal should occur at that time, the lever would be free to make further tilting movement in excess of the proper amount. The head on the stem engaging the face of the actuating lever prevents such withdrawal of the stem and insures the lever being stopped and held in the desired position while the 55 shot is being recorded by the phantom ball and until the apparatus is reset for a succeeding shot.

Another function of the disks or heads 206 is to prevent the full movement of any solenoid core other than the one first affected. For example, when a ball strikes between two of the cords for the side switches, both switches will be actuated, but the one on the core nearer the point of impact of the ball will operate just enough quicker than the other to cause the lever 70 75

192 to begin to trip before the solenoid of the other cord and switch can actuate its stem. When this does occur, the lever will be in position to be engaged by the head on that stem, thus preventing the stem passing beneath the lever.

5 In order to simulate as closely as possible the conditions of actual play, and to test and develop the skill of the player, mechanism has been provided for imparting to the phantom ball a retarding or accelerating or deflecting effect corresponding to the retarding or accelerating or deflecting action of the wind, and provision has been made for adjustment of the apparatus for any desired wind direction and velocity.

10 15 This mechanism, which for convenience is referred to generally as the wind deflection mechanism or device, is illustrated in Figs. 4 to 7, 11 and 12. It is located beneath the board or base 31 carrying the timing and projecting mechanism, and operates to impart tilting and swinging movements to the base and the mechanisms carried thereby. Such swinging and tilting movements take place at the same time that the projector is being tilted by the movement of the inclined cross-head and inclined guideways. Any 20 25 tilting of the base produces an increased or diminished forward travel of the spotlight or phantom ball, according to whether the wind is favoring or opposed. A swinging movement of the base, on the other hand, will cause a deflection of the phantom ball to one side or the other in a curved path of movement corresponding to the effect of the cross component of the wind in a most realistic manner, and calling upon the player to make due allowance therefor in exactly the same manner as upon the outdoor course.

30 35 The base or board 31 is mounted to provide for this tilting and swinging action in the following manner: A hollow, vertical spindle 211 is rotatably mounted upon the stem or standard 32 carried by the base 33, a ball 212 or other anti-friction thrust bearing being provided to insure free movement with minimum of friction. Fixed upon the top of the hollow spindle is the fork 213 in which the base 31 is mounted on the horizontal pivots 214. The pivotal point is such that the base and the parts mounted thereon shall be as nearly as possible in balance to give the freest and easiest tilting movements.

40 45 50 The tilting action is produced through the vertical movement of a sleeve 216 loosely mounted upon the hollow spindle 211, and provided at its upper end with a sleeve or collar 217 having a groove 218 in which is received a roll 219 on pin 220, at the lower end of the link 221 passing through guides 222 on the hollow spindle 211. A rocking lever 223, pivoted upon the upstanding arm of the bracket 224 extending laterally from the yoke 213, is connected at one end to the link 221 and at the other through the link 225 to a bracket 226 fixed upon the under side of the board or base 31.

55 60 65 Thus when the sleeve 217 is raised, the left hand or projector end of the board or base will be tilted downwardly to give a retarding effect to the phantom ball corresponding to a head wind. Conversely, when the sleeve 217 is lowered, the left hand or projector end of the base is tilted upwardly, increasing the movement of the spotlight or phantom ball and giving the effect of a following or helping wind.

70 75 The devices for actuating the sleeve 216 to tilt the base 31 comprise a spring, tensioned by the operator when the apparatus is preliminarily set and combined with a dashpot for controlling the

rate of movement of the parts, and thrown into operation by a solenoid which is itself controlled by the timer. The actuating spring is shown in Fig. 5 at 231, the dashpot at 232 and the solenoid at 233.

80 85 90 The connected mechanism between the spring and the vertically movable sleeve 216 is as follows: Pivoted to the lower end of the sleeve is the link 234, the upper end of which is pivotally connected to the sector 235, guided by the ears or guides 236 upon the sleeve. The sector is pivoted at 237 in a fixed support, (not shown), and its arcuate periphery 238 is engaged by the friction shoe 239 at the end of the rod 241. This shoe is U-shape in cross-section, the side walls forming 15 20 25 guides for the sector, and in the bottom of the channel is a strip of fibre or other suitable friction material so that longitudinal movement of the shoe will actuate the sector. A spring 242 attached at its lower end to a pin on the shoe and at its upper end to the pivot 237, holds the shoe in contact with the quadrant under sufficient pressure to prevent slippage between the parts in normal operation.

100 105 110 The rear end of the actuating rod 241 is pivotally connected to an adjustable crank pin mounted in the slot 244 in the horizontal disk 245 axially pivoted in any suitable manner. The crank pin shown in Figs. 5, 11 and 12, comprises the pin 246 passing through the slot 244 and having the head 247 at its lower end held by the undercut sides of the slot. The upper end of the pin is threaded as at 248 and carries a clamping nut 249. Pivoted upon the pin is a sleeve 252 the lower end of which has straight 155 200 250 sides to fit the slot 244 and be held from turning, the middle portion of which is cylindrical to form a bearing surface for the end of the rod 241, and the upper portion of which is formed with straight sides at an angle of 45° to those of the other end to receive the slotted arm 253 and hold it from turning and in fixed angular position relatively to the slot 244 in disk 245.

205 210 215 Tightening of the clamp nut 249 locks the adjustable crank pin and slotted arm in fixed position on the disk, but permits free pivotal movement of the actuating rod 241.

220 225 230 The mechanism for imparting rotational movement to the disk 245 to cause its crank arm to actuate the rod 241 comprises the arm and rod 255 having at one end the strap 256 surrounding the periphery of the disk, with the tightening bolt 257 and wing nut 258 for adjusting the frictional engagement between the strap and the disk. A spring 259 is provided between the head 255 of the bolt and the strap to permit adjustment of the friction. The purpose of this frictional engagement is so that the disk will normally be actuated by the swinging movement of the rod 255 and yet permit adjustment of the disk within 255 300 350 the strap in setting or adjusting the mechanism.

355 400 450 The arm 255 is actuated by the tension spring 231, the speed of its movement being controlled by the dashpot 232, see Fig. 4. This is accomplished by means of the bell-crank lever 262 pivoted at 263 upon a fixed portion of the machine, (not shown). The lower end of the pivotal arm of this bell-crank lever is bifurcated at 264 and engages the extension 265 on the arm 255. The end of the horizontal arm of the bell-crank lever 70 75 80 is connected to the piston rod 266 of the dashpot by means of the strap or stirrup 267, (see Fig. 6).

85 90 95 The piston rod 266 of the dashpot is hollow and receives the valve stem 268, having the tapered lower end 269 and threaded upper end 271.

with knurled head 272. Ports 273 are formed in the wall of the hollow piston rod 266 in position to be opened and closed to a greater or less extent by the tapered end 269 of the valve stem, 5 thereby controlling the rate of movement of the piston in the dashpot. The loosely fitting piston 274 is mounted upon the lower end of the hollow piston rod, which projects through the piston, thus providing a passage from above 10 the piston to beneath it, through the ports 273 and hollow rod.

The piston is provided with the openings 275 which are normally covered by the imperforate disk 276 fitting loosely on the piston rod. During 15 the operative or upward stroke of the piston, the disk closes these openings and the speed of movement of the piston is determined by the flow of the liquid from above to beneath the piston through ports 273 and hollow piston rod and 20 around the piston.

By adjusting the valve rod by means of the knurled head 272, the ports may be opened or closed to secure the desired speed of movement of the dashpot. During the downward or idle 25 strokes of the piston, the disk is free to rise, uncovering the openings and permitting the resetting of the parts quickly and with little effort.

The arm 255 is restrained from lateral movement by means of the pin 278 having its face 30 shaped to engage one or another of the ratchet teeth 279 in the locking bar 281. This bar is pivoted at 282 and is normally held in locking position by means of the tension spring 283, being actuated to release the bar 255 by the solenoid 233.

By adjusting the crank pin 246 in its slot 244 and the slotted arm 253 on the crank pin to radial distances from the disk center corresponding to the wind velocity assumed, any desired 40 acceleration or retardation, and any desired deflection, and any combination of such movements may be obtained and reproduced in the phantom ball.

In order to assist and guide the operator in adjusting this portion of the apparatus for the desired wind velocity, scales have been provided, one adjacent the slot 244 in the disk 245 and the other on the slotted bar 253. These scales are preferably so laid out that the parts will be 50 adjusted to the same reading on both scales, which will be the predetermined wind velocity.

The operator is further guided in setting these parts for a predetermined direction of wind by an arrow marked on the face of the disk 245 at 55 right angles to slot 244. This arrow points in the direction toward which the wind is blowing. For example, in Fig. 5 the wind is a head wind with a slight left to right component.

The frictional engagement between disk 245 and band 256 permits the disk to be turned to cause the arrow to point in the desired direction, relatively to the general direction of the fairway or hole being played, without interfering with the velocity adjustments. Thus the conditions 60 of actual play may be easily reproduced with a different wind direction, relatively, at each hole but with the same velocity, the varying effects on distance and directions being automatically reproduced in the movements of the phantom ball.

Since these wind deflection effects will be produced simultaneously with the tilting of the projector under the control of the timer mechanism, the phantom ball is given a regular and even 75 deflection, accelerating or retarding movement

from start to finish, which resembles in the most realistic manner the travel of a ball in the open.

The mechanism for imparting deflection to the phantom ball, as in the case of a cross wind, is generally similar to that for varying the extent 5 of its travel to indicate acceleration or retardation by the wind. It comprises the arm 293 clamped upon the hollow spindle 211 and having the arcuate outer end 294. This is engaged by the friction shoe 295, similar in construction 10 to the friction shoe 239, and held in close frictional engagement with the arcuate end 294 of the arm 293 by tension spring 296. The shoe 295 is mounted upon the actuating rod 298 pivoted at its opposite end to the slotted arm 253. 15

When the disk 245 is actuated by the spring 231 under control of the dashpot 232, the actuating rod 298 is given a longitudinal movement to turn the hollow spindle 211 which through the arms 213 swings the base 31 to the right or to 20 the left, according to the adjustment of the actuating parts, to impart a deflection to the phantom ball.

The control for rendering the wind deflection mechanism operative is through the solenoid 233 25 which is in a circuit in turn controlled by a contact or switch at the lower end of the latch lever 98. The connections and arrangement are such that the circuit is normally open at this point but will be closed by the action of spring 109 when 30 the timer solenoid 104 is de-energized, and remain closed until the quadrant has finished its operative stroke. This switch comprises a contact point 301 on the end of the adjusting screw having the knurled head 302 and mounted in the 35 bracket 303 on the base 31. The lower end of the latch lever 98 forms the other contact, a suitable electrical connection, not shown, being provided through such lever.

In order to maintain the circuit open when the apparatus is set and ready for use, and prior to the ball leaving the tee, the quadrant is formed of slightly longer radius, as shown at 305, (Fig. 10), adjacent the shoulder 100, so that when the parts are in latched position, as shown in Fig. 1, 40 the upper end of the latch lever 98 will be forced slightly to the right causing the lower end to move in the opposite direction and out of contact with the point 301. 45

Similarly the periphery of the quadrant adjacent the face of the stop shoulder 306 is also of slightly longer radius as shown at 307 in Fig. 10, so that when the quadrant is completing its stroke and the projector is reaching the end of its recording movement, such longer radius portion of the quadrant will actuate the latch lever slightly to break the contact with the point 301, de-energizing the solenoid 233 and throwing the latch mechanism into action to stop further movement of the wind deflection devices simultaneously with the stopping of the tilting movement of the projector under the action of the quadrant. 55

The electrical circuits for the timer, direction and wind deflection devices are shown diagrammatically in Fig. 28. The source of electricity may conveniently be the ordinary domestic alternating current through the leads 311 to the primary 312 of a transformer where the secondary 313 reduces the voltage to any desired safe and convenient amount. 60

The current is led from the secondary through the conductor 314 having parallel connections with each of the curtain switches, both the middle closed switch 141 and the side open switches as 65 185. Tracing the circuit through the closed mid- 70

idle switch 141, this leads through the conductor 315 to the timer solenoid 104, thence through the normally closed switches 200, which are arranged in series, to the contact screw 133 of the tee switch where the circuit stands normally open. The remainder of the circuit is through the switch lever 129, tee solenoid 118, and thence back to the outer end of the secondary by the conductors 316 and 317.

10 The circuits through the open or side switches 185 include the direction solenoids 196 and 198, each one in series with an open switch, and thence by a common lead 319 and conductor 317 back to the secondary 313.

15 The circuit for the wind deflection device includes the extension 321 from the lead 314, which extension is connected to the latch lever 98, thence through the contact 301, which is open at all times except while the projector is being tilted 20 by the timer quadrant, through conductor 322 to the solenoid 233, and by the return 323 and conductor 317 back to the transformer secondary.

25 The operation of the circuits is as follows: The ball being held on the tee and the timer, projector, direction, and wind deflection devices being properly set or adjusted with the phantom ball on the tee or "lie" on the pictorial fairway, the parts and switches will be in the position shown in Fig. 28. The instant the ball leaves the tee, the lever 30 129 contacts with the screw 133, closing the circuit through the tee solenoid 118, the middle curtain switch 141, and the timer solenoid 104, thereby setting the timer mechanism in operation by the release of the quadrant. During the flight of 35 the ball from tee to curtain the tee solenoid holds the tee switch closed, and the timer solenoid holds the wind deflection switch 301 open.

If the ball strikes the curtain near the middle, the middle closed switch 141 is momentarily 40 opened to break the circuit and de-energize the timer solenoid 104 and the tee solenoid 118. The tee switch instantly opens and remains open for the balance of the stroke of the timer, so that although the middle curtain switch 141 may immediately close, the circuit has been broken at the tee switch and cannot be reestablished until that switch is reset. The de-energizing of the timer solenoid 104 throws the clutch mechanism into action, and the tilting movement of the 45 projector begins and continues during the remainder of the stroke of the timer quadrant. At the same time the wind deflection circuit is closed at 301, the solenoid 233 is energized, and the wind deflection devices set in operation. 50 This circuit remains closed until broken at the end of the stroke of the timer quadrant and movement of the projector.

If, on the other hand, the ball strikes to one side of the middle of the curtain, so that instead 55 of opening the normally closed switch 141 it closes one of the normally open side switches 185, the effect of such closing is to actuate one or another of the direction solenoids 196, 198. The resulting movement of its core projects its stem 60 205 into the path of lever 172, trips the latch arm 186, and breaks the timer solenoid circuit at 200, all in rapid succession. The projector and wind deflection devices then function as above 65 described.

70 If the ball strikes the curtain at a point between two of the cords, so that two switches are actuated, this causes no difficulty as the switch which is first actuated will control and the later actuation of the other will be without effect.

75 It will be noted that when the parts are set

and ready for the player to make his stroke, there is no current in any of the circuits, and similarly, when the phantom ball has completed its recording movement, all the circuits are open.

In order to add another feature of realism to the use of the above described apparatus, an auxiliary curtain or screen may be provided extending from the floor upwardly a short distance across the front of the main screen, similar to a cross bunker or other obstruction. At the appropriate time this will be raised the proper height and the player required to "carry" it on his next stroke. If the ball is too low and is stopped by this auxiliary or bunker screen, none of the curtain switches will be actuated and the timer stroke will be completed without movement of the projector or travel of the phantom ball. This bunker screen, as shown at 331 (Figs. 22 and 23) is conveniently mounted upon a roller 20 332 pivoted in the brackets 333. The screen may be raised and held in position by cords 334 at each end.

While the present apparatus may be employed with the spotlight or phantom ball thrown upon the back curtain or a plain screen ruled or marked to indicate distances, a greater realistic effect may be obtained by providing a screen such as is shown at 83 in Fig. 29, upon which will be depicted in plan view a portion of a playing field, showing the position of the tee, the putting green and hole, and the various topographical features in connection therewith. If desired, each of these auxiliary screens or fairway pictures may be provided, each one representing a separate fairway or hole, one after another being 30 rolled off or hung up and the hole then displayed being played by the contestants. The home course of the owner of the apparatus may be shown on these picture screens, or one or another of the well known courses may be reproduced. With several sets of such screens a host may entertain his guests with matches over any of the world's famous courses. Preferably, however, the picture will be reproduced on the back curtain itself by means of lantern slides and a 40 projector such as 336 in Fig. 20.

In the particular screen shown in Fig. 29, the tee is indicated at 337 and the green at 338, with the objective hole 339. Guarding the green are the sand traps 341, while in front of the tee is the brook or stream 342. On each side of the fairway 243 is the rough 344, with the trees 345. Contour lines to indicate elevations and depressions could be added or arrows accompanied by figures could be placed at the proper locations to indicate the direction and distance the phantom ball should move, in addition to its automatically produced travel, to represent the effect of the slope of the ground. For the sake of clearness, however, these contour lines and arrows and figures have been omitted from the drawings.

In operation, the tee switch and the timer and projecting apparatus will be positioned in front of the open end of the cage and to one side of the mat or other teeing surface. In Fig. 20 is 65 shown in plan view the general arrangement, the tee switch being indicated at 351 and the timer apparatus at 352.

Assuming the proper electrical connections have been made, a convenient and satisfactory 70 order for the different steps in setting the apparatus for use is the following:

(1) Adjust the wind deflection devices for the predetermined velocity and direction of wind. The resetting is accomplished by pushing the end 75

of the actuating lever 255 back against the tension of spring 231 to initial position where it will be held by latch bar 281. The devices are then adjusted by loosening the clamping nut for the crank pin and positioning the latter in the slot in the disk at a distance from the center corresponding to the selected velocity. The slotted bar is similarly adjusted on the crank pin and the clamping nut is tightened. The disk is 5 then turned by hand within its encircling band or strap until the arrow points in the direction toward which the wind is assumed to be blowing.

(2) The ball is teed upon the pad 124, the tee switch being so positioned that the proper 10 tension will be put upon the switch parts to hold the switch open.

(3) The timer mechanism is set by pulling down on quadrant lever 101 against coiled spring 45, bringing the parts into the position shown in 15 Fig. 1.

(4) Still maintaining his hold upon handle 101, the player now tips the base vertically and swings it horizontally as shown in Fig. 1 until the spotlight or phantom ball rests upon the representation of the tee 337 on the picture screen or 20 the desired spot on the fairway if the tee shot has already been played.

(5) The projector is adjusted on the base 31 in accordance with the type of club which is to 25 be used in making the next shot. This is done by sliding the projector pedestal or base in its guides to the position, as indicated by the scale, which corresponds to that particular club.

(6) The direction actuating devices are quickly 30 set by swinging handle 176 first to one side and then to the other to tension the actuating springs 179 and 180 and latch the parts in operative position.

(7) The projector actuating mechanism, i. e., 35 the yoke with inclined slots, is adjusted for the direction in which the ball should be driven, either straight down the fairway or toward one side or the other according to the wind. If the tee shot has been made and the ball is off the line from tee to hole, allowance must be made.

The apparatus is now all ready, and the player 40 takes his stance and with the proper club for the shot to be made drives the ball against the middle of the curtain or screen 84 or to one side or the other, as the wind direction and velocity 45 may require or his skill will permit. The instant the ball leaves the tee the timer is set in operation as above described, but no visible effect is yet produced. As soon, however, as the ball 50 strikes the back curtain the projector begins its movement and the phantom ball starts away from the tee or "lie" on the fairway either directly towards the hole, if the player has been skilful, or to one side or the other if he is off direction or is making some allowance for the 55 wind.

As the phantom ball continues its movement under the control of the timer, the wind deflection devices are also operating and the ball is 60 accelerated or retarded or deflected, as the case may be, finally slowing down and coming to rest at a point on the screen corresponding to the position the player's ball would have reached normally in the open on a level fairway.

Let us assume that the hole illustrated on the 65 screen is being played; the distance is 385 yards, there is a slight cross wind from right to left, and the ball has been driven 210 yards. This first stroke is indicated by the broken line 353 70 and the stopping place of the ball is at 354. The

player now re-sets the apparatus and readjusts the base until the spotlight is upon the point 354. If desired, a hand operated projector spotlight, sticker, or other device may be placed upon the stopping point of the phantom ball to aid in re-setting the apparatus. 5

On the next shot the player has 175 yards to make to the green and he plays it with the proper iron, being careful not to overshoot the green. Unfortunately he is short, stopping at 355 in 10 front of the bunker, leaving him a forty yard pitch to the pin. He again resets the apparatus and with the proper club, such as a mashie niblic, pitches the ball against the back curtain, taking care to use only the same force that he would 15 need in the open for this distance. When the ball strikes the screen the projector will begin its movement, and if the shot is accurately played, the phantom ball will stop close to the hole at 20 356.

If the player overshoots the green and has to play back, he simply turns the slotted yoke upside down, so that the front end of the projector will be tilted downwardly to cause the phantom ball to move generally downwardly on the screen 25 instead of upwardly. Turning the yoke through 90° adjusts the projector for a pitch to the green following a "hole-high" shot to one side thereof.

Thus the player by the use of this apparatus 30 may exercise his skill and ability and secure not only valuable practice in driving the ball a long distance, but also in playing short shots or half shots, quarter shots, etc., as they are sometimes called.

If more than one player is to use the apparatus, 35 the mode of procedure is exactly the same, each player, before making his shot, setting the phantom ball where his ball rested at the end of his last previous stroke, as indicated by his sticker or spotlight of which four may be provided as illustrated at 361 in Fig. 20. Thus one apparatus 40 may serve for two, three, or any number of players.

If the fairway shown on the screen is provided 45 with slope arrows and numbers, each player, when his phantom ball comes to rest, will give an additional movement by hand to the phantom ball in the direction indicated by the nearest arrow and for a distance corresponding to the number accompanying such arrow, this additional movement of the phantom ball representing the 50 effect upon the "run" of the ball by the slope or inclination of the fairway.

While the accompanying drawings show, and the foregoing specification describes, what is 55 deemed at the present time to be the preferred form of the invention, it is to be understood that the invention is not limited thereto, but may be embodied in other forms and constructions without departing from the spirit of the invention as defined in the appended claims. 60

For example, for short or pitch shots the difference in relation between the time of flight and distance traveled may conveniently be compensated for by positioning the tee and timer apparatus nearer the curtain. In such case the teeing mat, switch and projector may be moved up to the positions indicated in dotted line at 362 in Fig. 20. 65

Again, a pond or other water hazard may be 70 represented by a cut away or transparent portion in the screen, or by a mirror, and by means of a photo-electric cell the projector mechanism may be stopped in its operative stroke where the phantom ball or spotlight passes over the water hazard at low velocity, thereby reproducing 75

ing the trapping of a ball which lacks sufficient velocity or "distance" to carry the water hazard.

Also, instead of employing the pin and cross-head connection between the quadrant and actuating rod, a cam mechanism may be substituted in order to give a different time characteristic to the actuation of the rod. Similarly guides 86 on the yoke, instead of being straight may be curved or cam-shaped, to produce the desired movement 10 of the projector.

Having thus described the present invention, what is claimed is:

1. In an apparatus for indicating the potential distance of travel of an object, the combination 15 with means having a predetermined extent of movement and set in operation when the object is set in motion, of an indicator, and mechanism operative when the object has traveled a predetermined portion of its potential travel to connect said indicator to said means whereby the remaining portion of the movement of said means will actuate the indicator to indicate the distance of potential travel of the object.
2. In an apparatus for indicating the potential 25 distance of travel of an object, the combination with a timer comprising a movable member and devices for imparting thereto a movement of predetermined extent, of an indicator, and a clutch for connecting the movable member and the indicator during the movement of the former.
3. In an apparatus for indicating the travel of an object, the combination with a projector for projecting a spot of light, of means for imparting continuous movement to the projector to 30 cause movement of the spot of light in representation of the travel of the object.
4. In an apparatus for indicating the travel of an object, the combination with a projector for projecting a spot of light, of a screen bearing 35 a representation of a playing field, and means for actuating the projector to cause the spot of light to travel over the screen.
5. In an apparatus for indicating the potential 40 distance of travel of an object, the combination with means for indicating the potential distance of travel of the object, of a curtain, devices adjacent the curtain and set in operation by the impact of the object on the curtain for actuating the indicating means to indicate both distance and varying extents of deviation from the 45 predetermined direction of flight of the object, and mechanism set in operation before the object strikes the curtain for controlling said actuating devices.
6. In an apparatus for indicating the flight 50 of an object, the combination with an indicator, of a single continuous curtain, a series of spaced flexible cords immediately behind the curtain, a curtain switch connected with each cord and 55 adapted to be actuated thereby when the cord is deflected by the impact of the object on the curtain, a solenoid connected to each switch, and devices controlled by the solenoids for actuating the indicator to indicate a deflection of the object from the intended direction of flight.

7. In an apparatus for indicating the potential distance of travel of an object, the combination 60 with a dash-pot having a movable member and means for imparting thereto a stroke of uniform extent, of an indicator, connections including a clutch between the member and the indicator, and devices for actuating the clutch during the movement of the member whereby the indicator is connected to the member during a 65 portion only of the movement of the latter and

is controlled thereby to indicate the potential distance of travel of the object.

8. In an apparatus for indicating the potential distance of travel of an object, the combination 70 with an indicator, of a dash-pot having a movable member, means for actuating the movable member an invariable predetermined distance, and connections between the movable member and the indicator whereby the movement of the indicator is controlled by the movement of said member.

9. In an apparatus for indicating the potential 75 distance of travel of an object, the combination with an indicator, of a dash-pot having a movable member, means for imparting to the movable member strokes of invariable predetermined extent, and devices for varying the rate of movement of said member in different portions of its stroke, and connections between the member and the indicator.

10. In an apparatus for indicating the potential 80 distance of travel of an object, the combination with an indicator, of a dash-pot having a movable member and a port, said port having different effective open areas for different portions 85 of the stroke of the member to vary the rate of movement of the member, and connections between the member and the indicator.

11. In an apparatus for indicating the potential 90 distance of travel of an object, the combination with an indicator, of a dash-pot having a movable member, connections between the member and the indicator including telescoping parts, and a clutch between said parts.

12. In an apparatus for indicating the potential 95 distance of travel of an object, the combination with an indicator, of mechanism for actuating the indicator comprising a movable member, means for actuating said member in accordance with the potential distance of travel of the object, and connections including a cam between the member and the indicator.

13. In an apparatus for indicating the potential 100 distance of travel of an object, the combination with an indicator, of a longitudinally movable member, means for actuating the member, a cam surface carried by the member, and connections for actuating the indicator from the cam surface.

14. In an apparatus for indicating the potential 105 distance of travel of an object, the combination with an indicator, of a longitudinally movable member, an inclined slotted guide carried by the member, a cross-head in said guide, and connections between the cross-head and the indicator.

15. In an apparatus for indicating the potential 110 distance of travel of an object, an indicator comprising a member pivoted to turn about axes at right angles to each other to indicate the potential distance and direction of travel of the object, and means independent of the object for actuating the member.

16. In an apparatus for indicating the potential 115 distance of travel of an object, an indicator comprising a member pivoted to turn about axes at right angles to each other to indicate the potential distance and direction of travel of the object, and longitudinally movable and rotatable means independent of the object for actuating the member.

17. In an apparatus for indicating the potential 120 distance of travel of an object, an indicator comprising a member pivoted to turn about axes at right angles to each other to indicate the potential distance and direction of travel of the object.

- 5 tential distance and direction of travel of the object, and means independent of the object for actuating the member said means comprising a longitudinally movable and rotatable element, 5 a slotted guide carried by said element, and a cross-head carried by the member and rotatable with the guide for actuating the member about the axes.
- 10 18. In an apparatus for indicating the potential distance of travel of an object, an indicator comprising a projector mounted to turn about vertical and horizontal axes for indicating by a movable spot of light the potential distance and direction of travel of the object, and means controlled by the velocity and direction of travel of the object through a predetermined distance for moving the projector about said axes.
- 15 19. In an apparatus for indicating the potential distance of travel of an object, an indicator comprising a projector mounted to turn about vertical and horizontal axes for indicating by a movable spot of light the potential distance and direction of travel of the object, means for moving the projector about said axes, and a support for 20 the projector movable at right angles to said axes to vary the extent of movements imparted by said means.
- 25 20. In an apparatus for indicating the potential distance of travel of a free object, the combination with an indicator, of devices having a predetermined extent of movement and set in operation when the travel of the object is initiated, and means controlled by the time duration of travel of the object to a predetermined point 30 for utilizing a portion only of the movement of said devices to actuate the indicator.
- 35 21. In an apparatus for indicating the potential distance of flight of a golf ball, the combination with an indicator, of electrically controlled devices for controlling the same including a tee switch comprising a contact, a spring contact member, a pad to support the ball, and a flexible connection between the pad and the spring contact whereby the weight of the ball will hold the 40 spring contact out of engagement with the contact.
- 45 22. In an apparatus for indicating the potential distance of flight of a golf ball, the combination with an indicator, of a tee switch comprising a fixed contact, a spring contact member, a pad to support the ball, and a flexible connection including an extensible spring between the pad and the spring contact member.
- 50 23. In an apparatus for indicating the potential distance of flight of a golf ball, of a tee switch comprising a fixed contact, a second fixed contact insulated therefrom, a spring contact member insulated from said contacts and adapted to engage therewith, a solenoid having a movable core, connections between the core and the spring contact member, a pad for supporting the ball, and a flexible connection between the pad and core, and electrical connections for energizing the 55 solenoid to hold the spring contact in engagement with the two fixed contacts.
- 55 24. In an apparatus for indicating the potential distance of travel of an object, the combination with a curtain, of a series of spaced curtain switches suspended independently of the curtain and adapted one or another to be actuated by the localized distortion of the curtain produced by the impact of the object.
- 60 25. In an apparatus for indicating the potential distance of travel of an object, the combination with a flexible curtain, of a flexible member immediately adjacent and disconnected from one face of the curtain, and a switch adapted to be actuated by the distortion of the member caused by the impact of the object on the opposite face of the curtain.
- 65 26. In an apparatus for indicating the potential distance of travel of an object, a flexible curtain, a vertically hanging cord adjacent one face of the curtain, a switch supported by the cord having a movable member attached to the cord and supporting the switch, and a spring normally holding the switch inoperatively and yielding to permit actuation of the switch upon the impact of the object on the opposite face of the curtain.
- 70 27. In an apparatus for indicating the direction of travel of an object, the combination with a single indicator, of a plurality of solenoids each corresponding to a predetermined direction, means responsive to the direction of the initial travel of the object for energizing the appropriate solenoid, and connections between the solenoids and said indicator.
- 75 28. In an apparatus for indicating the direction of travel of an object, the combination with a single indicator, of a plurality of solenoids each corresponding to a predetermined direction, of means responsive to the direction of the initial travel of the object for energizing the appropriate solenoid, and devices controlled by the solenoids for controlling said indicator.
- 80 29. In an apparatus for indicating the direction of travel of an object, the combination with a single indicator, of a plurality of solenoids each corresponding to a predetermined direction and each provided with a movable core, means for actuating the indicator, and stop devices controlled by the cores to limit the extent of movement of the indicator actuating mechanism to indicate the direction of travel.
- 85 30. In an apparatus for indicating the potential distance of flight of an object, the combination with an indicator, of means for indicating the normal distance of travel, and supplemental devices adjustable in advance by the operator in accordance with the predetermined wind velocity for varying the action of said means.
- 90 31. In an apparatus for indicating the direction of flight of an object, the combination with means for indicating the normal direction of flight, and supplemental devices adjustable in advance by the operator to a predetermined wind direction for the varying of the action of said means.
- 95 32. In an apparatus for indicating the potential distance and direction of flight of an object, the combination with an indicator, of means controlled by the velocity and direction of a predetermined portion of the flight of the object for actuating the indicator to indicate the normal distance and direction of such flight, and supplementary devices adjustable in advance by the operator to a predetermined velocity and direction of wind for imparting supplemental movement to the indicator.
- 100 33. In an apparatus for indicating the potential distance and direction of flight of an object, the combination with a projector for indicating by a movable spot of light the distance and direction of such flight, a rotatable and tipping support for the projector, and means for tipping and rotating said support to simulate the effect of the velocity and direction of the wind on the flight of the object.
- 105 34. In an apparatus for indicating the potential travel of an object, the combination with a screen, of means for projecting on the screen the

representation of a playing field, a projector for indicating by a spot of light the travel of the object over the projected field, and means responsive to the initial portion of travel of the object for controlling the spot light projector.

35. In an apparatus for indicating the potential distance of travel of an object, the combination with the representation of a playing field, of a pivoted projector for causing a spotlight to travel over said representation to indicate the travel of the object, means responsive to the initial velocity of the object for tipping the projector in one direction to indicate the normal travel of the object, and reversing devices for causing said means to tip the projector in the opposite direction to represent the travel of the object in the opposite direction.

36. In an apparatus for indicating the potential travel of a golf ball, the combination with a representation of a fairway, of a projector for projecting a spot of light on such representation, and means for actuating the projector to cause the spot of light to travel over the fairway both longitudinally and laterally of such fairway in representation of the distance and direction of travel of the golf ball.

37. In an apparatus for indicating the potential travel of a free golf ball, the combination with a representation of a fairway, of an indicator, and means controlled by the starting and stopping of the free ball for actuating said indicator to indicate on such representation the extent of potential movement of a golf ball both longitudinally and laterally of such fairway.

38. In an apparatus for indicating the potential travel of a golf ball, the combination with a curtain to receive the impact of a driven golf ball, of a projector for throwing upon the curtain a pictorial representation of a fairway, a second projector for throwing a spot of light on such projected representation, and means for actuating the second projector to cause the spot of light to travel over the representation of the fairway in simulation of the movement of the golf ball over the same.

39. In an apparatus for indicating the potential travel of a golf ball, the combination with a representation of a fairway, of a projector for projecting a spot of light on such representation, and means for actuating the projector to cause the spot of light to travel over the fairway in any direction in representation of the distance and direction of travel of the golf ball.

40. In an apparatus for indicating the potential distance of travel of an object, the combination with means for stopping the object after a travel of predetermined length, of devices and actuating mechanism for imparting movement to said devices, said stopping means initiating the movement of the devices, and means operating in accordance with the duration of time required by the object to travel the predetermined distance for controlling the movement imparted to said devices by the actuating mechanism to indicate the potential distance of travel of the object.

41. In an apparatus for indicating the potential distance of travel of an object, the combination with an indicator, of means operating in accordance with the time duration of travel of the object from the initiation thereof to a predetermined point for actuating the indicator in accordance with such time duration to indicate the potential distance of travel of the object.

42. In an apparatus for indicating the potential distance of travel of an object, the combination

with a projector for indicating by a movable spot of light the potential distance of travel of the object, of means for actuating the projector, and devices operating in accordance with the duration of time required by the object to travel a predetermined distance for controlling the operation of said actuating means.

43. In an apparatus for indicating the potential distance of travel of a golf ball from the tee, the combination with an indicator, of actuating means therefor, and devices set in operation when the ball leaves the tee for controlling the operation of said actuating means.

44. In an apparatus for indicating the potential distance of flight of an object, the combination with a curtain, of an indicator, means for actuating the indicator, and controlling devices thrown into operation before the object strikes the curtain for throwing the actuating means into operation when the object strikes the curtain.

45. In an apparatus for indicating the potential distance of travel of a golf ball from the tee, the combination with indicating means, of a tee switch, a curtain switch, and actuating mechanism for the indicator, connections between the tee switch and the actuating mechanism for setting said mechanism in operation when the ball leaves the tee, and connections between the curtain switch and the actuating mechanism for rendering said mechanism operative to actuate the indicating means.

46. In an apparatus for indicating the potential travel of a golf ball, the combination with a common indicator for indicating both the potential distance of travel of the ball and the lateral deflections from the intended direction of travel, of a curtain, and actuating means for the indicator, said means operating in accordance with the duration of time required by the ball to travel from tee to curtain to cause the indicator to indicate the distance of travel, and also operating in accordance with the position of impact of the ball on the curtain to cause the indicator to indicate the direction of travel.

47. In an apparatus for indicating the potential distance of flight of an object, the combination with an indicator, actuating mechanism therefor, and devices affecting the operation of said mechanism to vary the actuation of the indicator in simulation of the accelerating, retarding, and deflecting effects of wind on the flight of the object.

48. In an apparatus for indicating the distance of travel of a free object, the combination with a pivotally mounted device, of means for moving the device about its pivot to indicate the distance of potential travel of the object, mechanism for actuating said means, said mechanism being controlled by the initial portion of travel of the free object, and means for energizing the mechanism independently of the movement of the object.

49. In an apparatus for indicating the distance of travel of a free object, the combination with a device mounted to turn, of actuating mechanism for turning the device to indicate the direction of travel of the free object, said means being controlled in accordance with the direction of initial travel of the free object and means for energizing the mechanism independently of the movement of the object.

50. In an apparatus for indicating the potential travel of a golf ball, the combination with a curtain to receive a free ball driven from a tee, of a representation of a playing field, indicating

means for indicating directly on the field both longitudinally and laterally thereof the relative position of the ball if the ball had terminated its potential travel, and mechanism for actuating the indicator in accordance with the velocity and direction of movement of the ball from tee to curtain.

5 51. In an apparatus for indicating the potential distance of travel of a golf ball, the combination with a curtain to receive a free ball driven by a club from a tee, of an indicator, and means independent of the club for actuating the indicator in forward and in reverse directions in accordance with the velocity of the ball from tee to 10 curtain.

15 52. In an apparatus for indicating the potential travel of a golf ball, the combination with a screen, of a projector for throwing upon the screen a pictorial representation of a fairway, a second projector for throwing upon such fairway the representation of a ball, and means for actuating the second projector to cause it to indicate on the representation of the fairway the potential travel of the ball in simulation of the 20 movement of a golf ball over a fairway.

25 53. In an apparatus for indicating the potential travel of an object, the combination with indicating devices, of actuating mechanism therefor, said mechanism operating in accordance with the duration of time required for a predetermined extent of movement of the object to cause the indicating devices to indicate the potential distance of travel of the object in accordance with such time duration.

30 35 54. In an apparatus for indicating the potential distance of travel of an object, the combination with an indicator, of means set in operation when the object is set in motion, said means operating in accordance with the duration of time required by the object to travel a predetermined distance to cause the indicating devices to indicate the potential distance of travel in accordance with such time duration.

35 40 55. In an apparatus for indicating the potential travel of a golf ball, the combination with a representation of a fairway, of a curtain to receive a free ball driven from a tee, an indicator, and actuating mechanism for the indicator to indicate on such representation the extent of potential movement of the ball in any direction on such representation, said mechanism operat-

ing in accordance with the duration of time required to travel from tee to curtain.

5 56. In an apparatus for indicating the potential distance of flight of a golf ball, the combination with an indicator, of electrically controlled devices for controlling the indicator including a tee switch having a contact member the initial operative movement of which is controlled by the ball.

10 57. In an apparatus for indicating the potential distance of flight of a golf ball, the combination with an indicator, of electrically controlled devices for controlling the indicator including a tee switch having a contact member rendered operative when the ball leaves the tee.

15 58. In a golf ball driving device, a tee from which a ball is to be driven, and means operatively connected to said tee and to a point spaced from said tee to determine the approximate distance a ball driven from said tee would travel if uninterrupted in its flight, by automatically timing the flight of the ball from the tee to the said point spaced from said tee.

20 25 59. In a golf ball driving device, a tee from which a ball is to be driven, and means operatively connected to said tee and to a point spaced from said tee to translate the time interval required by the flight of the ball from the tee to said point spaced from the tee into the approximate distance the driven ball would travel if uninterrupted in its flight.

25 30 60. In a golf ball driving device, a driving tee from which a ball is to be driven, a target spaced from said tee, and means operatively connected to the tee and target and operated by driving a ball from the tee to the target to determine the approximate distance of the flight of the ball from the time interval required by the ball to travel from tee to target.

35 40 61. In a golf ball driving device, a driving tee from which the ball is adapted to be driven, a target spaced from said tee, and means operatively connected to the tee and target and operated by driving a ball from the tee to the target to time the flight of the ball from the tee to the 45 target, and means to translate the time interval of the flight of the ball from tee to target into the distance the ball would have traveled if it had not been stopped by the target.

50 JOHN F. VAUGHAN.

CERTIFICATE OF CORRECTION.

Patent No. 2,121,750.

June 21, 1938.

JOHN F. VAUGHAN.

It is hereby certified that error appears in the printed specification of the above numbered patent requiring correction as follows: Page 13, second column, line 12, claim 26, for the word "inoperatively" read inoperative; line 20, claim 27, for "energizing" read energizing; and that the said Letters Patent should be read with this correction therein that the same may conform to the record of the case in the Patent Office.

Signed and sealed this 30th day of August, A. D. 1938.

Henry Van Arsdale

(Seal)

Acting Commissioner of Patents.
